UNITED STATES PATENT OFFICE.

GEORGE WARD BIDWELL, OF NEW HAVEN, CONNECTICUT.

DESIGN FOR A CLOCK-CASE.

SPECIFICATION forming part of Design No. 19,269, dated August 20, 1889.

Application filed May 10, 1889. Serial No. 310,947. Term of patent 7 years.

To all whom it may concern:

Be it known that I, GEORGE WARD BIDWELL, a citizen of the United States, residing at New Haven, in the county of New Haven and State of Connecticut, have invented and produced a new and original Design for Clock-Cases, of which the following is a specification, reference being had to the accompanying drawings, forming part thereof.

10 Figure 1 is a front view of a clock-case representing a frog-shaped figure holding in its mouth an elliptical portion or case proper, and Fig. 2 is a side view of the same.

15 A represents the figure having the shape of a frog, but the mouth of which is proportionately larger than is usual in frogs, thus adding grotesqueness to the design. In the open

mouth of the figure is held the case proper B, for containing the dial. The case proper is a band portion and a sash concentric therewith, as shown, and is substantially elliptical, the longest axis of the ellipse extending toward the right and left sides of the mouth, as shown in Fig. 1.

20 I claim—

The design for a clock-case herein shown and described, the same consisting of the frog-shaped figure A, holding in its mouth the elliptical portion or case proper B, as set forth.

25 GEORGE WARD BIDWELL.
